UNITED STATES PATENT OFFICE.

STEPHEN EMETT BURKE, OF EDON, OHIO.

GRATE FOR FURNACES.

SPECIFICATION forming part of Letters Patent No. 323,290, dated July 28, 1885.

Application filed May 9, 1884. (No model.)

To all whom it may concern:

Be it known that I, STEPHEN EMETT BURKE, a citizen of the United States, residing at Edon, in the county of Williams and State of Ohio, 5 have invented certain new and useful Improvements in Grates for Furnaces for Steam-Engines; and I do hereby declare the following to be a full, clear, and exact description of the invention, such as will enable others skilled in 10 the art to which it appertains to make and use the same.

My invention relates to grates for furnaces for steam-engines, and has for its object to provide means for shaking the grate to free 15 the draft, which shall be simple, inexpensive, and efficient; and it consists in the construction and the combination of parts, which will be hereinafter particularly described, and then specifically defined by the claims.

20 Figure 1 is a vertical longitudinal section through the furnace; Fig. 2, a perspective of one of the supporting and shaking shafts, and Fig. 3 a plan of the grate with portions broken away.

25 In the drawings, the letter A designates the masonry walls of the furnace, of any approved form, supporting the boiler B, and provided in its front with the door D, for introducing the fuel, and with the draft-door E, while F 30 designates the fire-box. These parts may all be of any preferred well-known construction, and will not be further described, as such are not my invention.

The grate is composed of a series of bars, G, 35 flat on the top and preferably inclined on the bottom from the center toward both ends, and near each end having a notch, H, preferably V-shaped, formed in the bottom face. The grate is supported at the front and rear by a 40 rod or shaft, I, the lower face of which, preferably at or near its ends only, is formed with V or wedge shaped pivots a, which rest in recesses or depressions b, preferably V or wedge shaped, formed in a plate, J, which is set into 45 the side walls of the furnace, as shown, while the upper face of the shaft is formed with a ledge, c, preferably V or wedge shaped, which fits into the notch of the grate-bar, and also with a shoulder or bumper, d, intermediate of 50 the pivots and ledge, and preferably V or wedge shaped, as shown.

By reason of the sharp angles presented, the form of the ledges, pivots, and shoulder shown is preferred; but I do not intend limiting myself to such exact forms, when other forms embodying the said three parts can be used to 55 good purpose.

The shafts constructed as described are placed at both front and rear ends of the grate, with their shoulders toward each other, and 60 the shaft next to the furnace-front is provided with a lever, K, which extends through the wall, as shown, and by which the shaft can be oscillated.

When the parts are applied as described 65 and shown, the grate is supported on pivots, which enable it to be moved with perfect ease back and forth to free it from ashes, and thereby increase the draft.

The movement imparted to the grate by depressing or elevating the lever is an alternately rising and falling motion, and also a reciprocatory motion, to which is added a jarring motion at each reciprocation of the grate, first at one end and then at the other end, caused 70 by the shoulders or bumpers on the shafts striking each grate-bar. The effect thus produced is a complete and easy sifting of the ashes from the grate and consequent increase 75 of draft.

80 The wedge-shaped pivots are shown at opposite ends of the shaft; but the effect is the same as if they extended from end to end, and less material is required.

I am aware that it is old to support grate-bars on rods formed with two sets of pivots fitting in recesses in the bars, the said pivots acting as cog-teeth of the same radius on a wheel to move the grate-bars back and forth; but my invention differs therefrom in supporting 85 the grate-bars or grate at both ends on ledges projecting from shafts, and providing the same shafts with bumpers having a different radius from the ledges, whereby, in addition to the oscillatory and reciprocatory motion of the grate, there is a jarring motion imparted to it in the oscillation of the shafts.

Having described my invention and set forth its merits, what I claim is—

1. The combination, with the movable grate-bars notched at both ends, of the supporting shafts formed with pivots on their lower edges,

2
with ledges on their upper faces entering the notches of the grate-bars and supporting the latter, and with shoulders or bumpers on their inner opposing faces intermediate of the ledges and pivots, the same ledges supporting the grate-bars at both ends of their reciprocation, whereby the grate-bars will be oscillated, reciprocated, and jarred, substantially as and for the purposes set forth.

10 2. The combination, with the movable grate-bars notched at both ends, of the shafts formed on their lower faces with wedge-shaped pivots, on their upper faces with wedge-shaped ledges,

and on their inner opposing faces intermediate of the ledges and pivots with wedge-shaped 15 bumpers or shoulders, the ledges fitting in the notches of the grate-bars and supporting the latter at both ends of their reciprocation, and recessed plates for the pivots to rest in, substantially as and for the purposes set forth. 20

In testimony whereof I affix my signature in presence of two witnesses.

STEPHEN EMETT BURKE.
